UNITED STATES PATENT OFFICE.

MATTHEW T. CHAPMAN, OF AURORA, ILLINOIS.

WELL-SINKING APPARATUS.

No. 833,200.

Specification of Letters Patent.

Patented Oct. 16, 1906.

Application filed July 15, 1901. Serial No. 68,883.

To all whom it may concern:

Be it known that I, MATTHEW T. CHAPMAN, a citizen of the United States, residing at Aurora, in the county of Kane and State of Illinois, have invented certain new and useful Improvements in Well-Sinking Apparatus, of which the following is a specification, reference being had to the accompanying drawings.

10 My invention relates to apparatus for sinking wells, and has special reference to apparatus designed for sinking wells to great depth.

It has for its object to provide certain improvements in well-sinking apparatus, as hereinafter described and as illustrated in the drawings.

What I regard as new will be set forth in the claims.

20 In the drawings, Figure 1 is a plan view of the turn-table, partly in section. Fig. 2 is a side elevation thereof, partly in section. Fig. 3 is a plan view of the turn-table, the gripping devices being illustrated in position thereon. Fig. 4 is a partial vertical section on line 25 5 5 of Fig. 3. Fig. 5 is a partial vertical section on line 6 6 of Fig. 3. Fig. 6 is an enlarged detail, being a partial vertical section, illustrating in part the adjusting devices for 30 adjusting the gripping devices. Fig. 7 is a partial horizontal section of one of the sprocket-wheels. Fig. 8 is an enlarged detail, being a vertical section of part of the turn-table, showing one of the clamping devices. Fig. 9 is a vertical section on line 35 10 of Fig. 8, and Fig. 10 is a horizontal section on line 11 11 of Fig. 8.

It will be understood that in well-sinking apparatus of the type with which my present 40 invention has more particularly to do the pipe which is to form the tube or casing of the well, and which is usually termed the "well-tube," is employed for boring the first part of the well, its lower end being provided with a 45 suitable boring device. The well-tube, suspended from a derrick or other suitable support, is rotated about a vertical axis by means of suitable clamping devices which grip it and cause it to rotate, meanwhile permitting it to move endwise, and it is with 50 such gripping mechanism that my present invention has more particularly to do.

As will be observed from the examination 55 of the drawings, the gripping devices are mounted upon a turn-table 30, which is pro-

vided with a central annular opening through which the well-tube and boring-tube pass. The turn-table is provided at its under side with an annular channel 31, which receives a series of antifriction-rollers 32, supported in 60 an annular groove 33 in a bed 34, so that the turn-table 30 is adapted to rotate freely on the rollers 32. The turn-table 30 is caused to rotate by means of a bevel-pinion 35, mounted on a horizontal shaft 36, journaled in a suitable bearing 37 and rotated from any suitable source of power. The pinion 35 meshes with an annular rack 38, carried at the under side of the turn-table 30, as shown in Fig. 2, so that by rotating said pinion the turn-table 70 may be caused to rotate on the rollers 32. While rotating, the turn-table is held down in position by clamps 39, secured to the base 40 of the turn-table and having teeth 41, which project into an annular groove 42, arranged below the rack 38, as shown in Fig. 2. Preferably four of the clamps 39 are provided, as shown in Fig. 1.

The arrangement of the gripping devices on the turn-table is best shown in Fig. 3, 80 from an inspection of which it will be seen that there are three clamping devices A, B, and C, respectively, arranged equally distant apart around the central opening of the turn-table in position to engage the well-tube 26. 85 Each of said clamping devices is arranged to move radially toward and from the tube to be clamped, sliding on the turn-table. As shown in Fig. 4, each of the clamping devices consists of a corrugated roller 43, mounted 90 on a horizontal axis 44, carried in a frame 45, U-shaped in cross-section, which rests upon the turn-table. The inner portion of each roller 43—that is to say, the portion nearest the center of the turn-table—projects beyond 95 the frame 45 sufficiently to enable it to engage the tube to be clamped. The frames 45 are adapted to slide radially on the turn-table, being provided with laterally-projecting flanges 46, embraced by guide-plates 47, secured to the turn-table, as shown in Fig. 4. In order to hold the rollers 43 properly in operative position and prevent them from vibrating laterally, side bearing-plates 48 are provided, which are secured to the sides of 105 the frame 45 and adjacent to the rollers 43, and between said plates 48 and the ends of the rollers antifriction-balls are provided, as shown in Fig. 4, thus providing end bearings for said rollers. Roller-bearings 50 are also 110

provided around the axis 44 on each roller, so that they may be rotated more freely.

In the form of clamp shown in Figs. 4 and 5 the rollers 43 are mounted on axes 44, which are secured directly in the frames 45, and in this construction the clamping-rollers 43 cannot move vertically. In some cases, however, and particularly where it is frequently necessary to "jump" the well-tube, it is desirable to provide for lifting the clamping-rollers out of engagement with the tube to be clamped, and I provide for such movement by mounting the axes 44 of the said rollers 43 in swinging yokes 51, pivoted upon horizontal axes 52, mounted in the frames 45, as best shown in Fig. 8. By this construction each roller, with its yoke 51, may be rocked about its axis 52 to carry it out of engagement with the well-tube and when released will return to such engagement. 53 indicates an eccentric stop arranged under the side portions of each yoke 51 on a shaft 51^a, journaled in the frame 45, as shown in Figs. 8 and 9. By rocking the shaft 51^a the stops 53 may be turned to swing the yoke 51 upward and carry the roller 43 up out of operative engagement with the boring-tube. When turned down, the stops 53 permit the yoke to descend to operative position and prevent it from descending too far. Each shaft 51^a is provided with a ratchet-wheel 52^a and pawl 53^a to hold it against rotation when the stop 53 is turned up. By using the swinging yoke it is much easier to lower the well-tube or the boring-tube into the well, since the clamping-rollers may be readily moved out of engagement to permit the passage of couplings.

The different clamping devices A B C are adjusted radially to adapt them to different-sized tubes by means of adjusting-rods *a b c*. (Shown in Fig. 3.) Each of said rods has a screw-threaded inner end, which is fitted in a threaded block 54, secured to each of the frames 45, as shown in Fig. 8. Between its ends each of said rods is fitted in a bearing-block 55, secured to the turn-table 30. To prevent the rods *a b c* from moving longitudinally in said bearing-blocks 55, a collar 56 is provided at one side of said block and a bevel-gear 57 at the other side, the bevel-gear being keyed to the rod, as shown in Fig. 8, where a feather 58 is shown. By this construction when the rods *a b*, and *c* are rotated the frames 45 will be caused to move radially between the guide-plates 47. The arrangement of the screw-threads in each of the rods *a b c* is such that similar rotation of said rods will cause the corresponding clamping devices to move in the same direction. The outer ends of the rods *a b c* are square, as shown at 59 in Fig. 3, so that by the use of a tool said rods may be rotated to adjust the clamping devices. In order to operate said clamping devices in unison, connecting-rods 60, 61 are provided, having, respectively,

bevel-gears 62 63 and 64 65 at their ends. The rod 60 extends between the gears 57, carried by rods *a* and *b*, its gears 62 63 meshing with the gears 57, carried by the rods *a* and *b*, as shown in Fig. 3. Similarly, the gears 64 65, carried by the rods 61, mesh with the gears 57 of rods *b* and *c*, so that by rotating any one of the rods *a*, *b*, or *c* both the other rods may be rotated simultaneously and to an equal extent. While the adjusting devices thus far described provide for easy and accurate adjustment of the different clamping devices when the turn-table is at rest, they cannot be conveniently operated while it is rotated. I have therefore provided means by which the clamping devices may be readily adjusted without stopping the turn-table. Such devices are best shown in Figs. 3, 4, 5, 6, and 7. As shown in said figures, each of the rods *a b c* carries near its outer end a sprocket-wheel 66, and said sprocket-wheels engage a chain 67, which extends around the turn-table and bears upon the peripheries of said wheels. Said chain 67 also passes around a series of sprocket-wheels 68, mounted on vertical shafts 69, rising from the turn-table 30, as shown in Fig. 6. One of said sprocket-wheels 68 is placed at each side of and adjacent to each sprocket-wheel 66, and they serve to hold the chain 67 properly in engagement with the sprocket-wheels 66 and also provide for moving said chain to partly rotate the sprocket-wheels and adjust the position of the clamping devices, as will be hereinafter described.

Above each sprocket-wheel 68 on each of the shafts 69 is a cross-head 70, carrying two upright pins 71 at opposite sides of the shaft, as shown in Figs. 3 to 6, said cross-heads being keyed to the shafts 69, as are also the sprocket-wheels 68, so that by rotating the shafts 69 the sprocket-wheels 68 may also be rotated. The object of the cross-heads 70 and pins 71 is to provide for rotating the sprocket-wheels 68 while the turn-table is in rotation, the operation being to place a crowbar upon one of the cross-heads, so as to project between the two pins carried by it, when by holding the outer end of the bar fixedly as the turn-table rotates the cross-head, and consequently the sprocket-wheel 68 adjacent it, will be rotated to a greater or less extent, thereby adjusting the position of the chain 67 and correspondingly adjusting the clamping devices A, B, and C. In order to provide for reversely adjusting the chain 67, a gear 72 is provided, mounted on a vertical shaft 73, carried by the turn-table 30, said gear being placed adjacent to one of the shafts 69 and being adapted to engage a gear 74, carried by said shaft below its sprocket-wheel 68, as shown in Fig. 6.

In the construction shown the gear 72 carries four pins 75, which rise from the upper

surface thereof and are arranged equally distant apart. By placing a crowbar between two of the pins 75 the gear 72 may be turned upon its pivot, and consequently through 5 the gear 74 will rotate the sprocket-wheels 68; but such rotation will be in a direction opposite that in which said sprocket-wheels are rotated when the crowbar is placed between the pins 71 of one of the cross-heads 10 70, because the direction of such rotation will be reversed by reason of its being transmitted from the gear 72 to the gear 74. It will thus be seen that notwithstanding the fact that the turn-table rotates continuously 15 in the same direction the chain 67 may be moved in either direction to adjust the clamping devices backward or forward without stopping the turn-table by placing a proper tool between the pins 71 of one of the 20 cross-heads 70 or between the pins 75 of the gear 72.

While I have described in detail my improvements as illustrated in the accompanying drawings, I do not wish to be restricted 25 to the specific details of the construction described, except in so far as such details are particularly claimed.

That which I claim as my invention, and desire to secure by Letters Patent, is—

30 1. In a well-sinking apparatus, the combination of a turn-table, a support carried thereby and arranged to swing upward from a horizontal plane, and gripping means carried by said support and adapted to engage the 35 boring-tube, whereby said gripping means may be moved out of operative engagement with the boring-tube when the boring-tube is lifted.

2. A gripping device for well-sinking apparatus, comprising a suitable support, a 40 swinging frame mounted thereon and arranged to swing upward from a horizontal plane, and a rotary gripping-disk mounted in said frame and adapted to rotate on a horizontal axis.

45 3. A gripping device for well-sinking apparatus, comprising a suitable support, a swinging frame mounted therein and arranged to swing upward from a horizontal plane, a rotary gripping-disk mounted in said frame and adapted to rotate on a horizontal axis, and means for adjusting said gripping-disk toward and from the article to be clamped, substantially as described.

50 4. A gripping device for well-sinking apparatus, comprising a suitable support, a rotary gripping-disk mounted therein and adapted to rotate on a horizontal axis, and lateral bearing-plates at the sides of said 55 gripping-disk between said gripping-disk and its support, substantially as described.

5. A gripping device for well-sinking apparatus, comprising a yoke, a rotary gripping-disk mounted therein and adapted to 60 rotate on a horizontal axis, lateral bearing-

plates at the sides of said gripping-disk between said disk and said yoke, substantially as described.

6. In a well-sinking apparatus, the combination of a turn-table, supporting devices carried by said turn-table, said supporting devices being arranged to travel toward and from the boring-tube, gripping devices carried by said supporting devices and adapted to grip the boring-tube, and means for positively moving said gripping devices simultaneously toward and from said boring-tube. 70

7. In a well-sinking apparatus, the combination of a turn-table, supporting devices carried by said turn-table and disposed triangularly thereupon, said supporting devices being arranged to travel toward and from the 80 boring-tube, gripping devices carried by said supporting devices and adapted to grip the boring-tube, and means for positively moving said gripping devices simultaneously toward and from said boring-tube. 85

8. In a well-sinking apparatus, the combination of a turn-table, supporting devices carried by said turn-table, said supporting devices being arranged to travel radially toward and from the boring-tube, gripping devices carried by said supporting devices and adapted to grip the boring-tube, and means for positively moving said gripping devices 90 simultaneously toward and from said boring-tube. 95

9. In a well-sinking apparatus, the combination of a turn-table, supporting devices carried by said turn-table, said supporting devices being arranged to travel toward and from the boring-tube, gripping devices carried by said supporting devices and adapted to grip the boring-tube; and means independent 100 of the rotation of the turn-table for positively moving said gripping devices simultaneously toward and from said boring-tube. 105

10. In a well-sinking apparatus, the combination of a turn-table, supporting devices carried by said turn-table, said supporting devices being arranged to travel radially toward and from the boring-tube, gripping devices carried by said supporting devices and adapted to grip the boring-tube, and means independent 110 of the rotation of the turn-table for positively moving said gripping devices simultaneously toward and from said boring-tube. 115

11. In a well-sinking apparatus, the combination of a turn-table, supporting devices carried by said turn-table, said supporting devices being arranged to travel toward and from the boring-tube, gripping devices carried by said supporting devices and adapted to grip the boring-tube, and means adapted 120 to be operated while the turn-table is rotating for positively moving said gripping devices 125 toward and from the boring-tube.

12. In a well-sinking apparatus, the combination of a turn-table, supporting devices 130

- carried by said turn-table, said supporting devices being arranged to travel toward and from the boring-tube, gripping devices carried by said supporting devices and adapted 5 to grip the boring-tube, and means carried by the turn-table for positively moving said gripping devices simultaneously toward and from said boring-tube.
13. In a well-sinking apparatus, the combination of a turn-table, supporting devices carried by said turn-table, said supporting devices being arranged to travel radially toward and from the boring-tube, gripping devices carried by said supporting devices and adapted to grip the boring-tube, and means carried by the turn-table for positively moving said gripping devices simultaneously toward and from said boring-tube.
14. In a well-sinking apparatus, the combination of a turn-table, gripping devices carried thereby and movable radially thereon, a shaft connected to each of said gripping devices and adapted to be rotated for moving the same toward and from the tube to be gripped, and connecting devices carried by the turn-table connecting the shafts of the different gripping devices for rotating them simultaneously, substantially as described.
15. In a well-sinking apparatus, the combination of a turn-table, gripping devices carried thereby and movable radially thereon, a radially-disposed shaft connected to each of said gripping devices and adapted to be rotated for moving the same toward and from the tube to be gripped, and connecting-shafts and gears connecting the shafts of the different gripping devices, for adjusting said gripping devices simultaneously, substantially as described.
16. In a well-sinking apparatus, the combination of a turn-table, gripping devices carried thereby and movable radially thereon toward and from the tube to be gripped, radially-disposed shafts connected to said gripping devices for adjusting them, each of said shafts carrying a sprocket-wheel, a chain connecting the sprocket-wheels of the different shafts, and means for operating said chain to rotate said sprocket-wheels and adjust the position of said gripping devices, substantially as described.
17. In a well-sinking apparatus, the combination of a turn-table, gripping devices carried thereby and movable thereon toward and from the tube to be gripped, radially-disposed shafts connected to said gripping devices for adjusting them, each of said shafts carrying a sprocket-wheel, a chain connecting the sprocket-wheels of the different shafts, and means for operating said chain while the turn-table is rotating, to rotate said sprocket-wheels and adjust the position of said gripping devices, substantially as described.
18. In a well-sinking apparatus, the com-

bination of a turn-table, gripping devices carried thereby and movable thereon toward and from the tube to be gripped, shafts connected to said gripping devices for adjusting them, each of said shafts carrying a sprocket-wheel, a chain connecting the sprocket-wheels of the different shafts, means for operating said chain while the turn-table is rotating, to rotate said sprocket-wheels and adjust the position of said gripping devices, 70 vertical shafts carried by said turn-table at opposite sides of and adjacent to each of said first-mentioned shafts, sprocket-wheels mounted on said vertical shafts, and cross-heads carried by said shafts, said cross-heads having projecting pins, substantially as described.

19. In a well-sinking apparatus, the combination of a turn-table, gripping devices carried thereby and movable thereon toward and from the tube to be gripped, shafts connected to said gripping devices for adjusting them, each of said shafts carrying a sprocket-wheel, a chain connecting the sprocket-wheels of the different shafts, means for operating 85 said chain while the turn-table is rotating, to rotate said sprocket-wheels and adjust the position of said gripping devices, vertical shafts carried by said turn-table at opposite sides of and adjacent to each of said first-mentioned shafts, sprocket-wheels mounted on said vertical shafts, cross-heads carried by said shafts, said cross-heads having projecting pins, a gear mounted on one of said vertical shafts, and a reversing-gear carried by said turn-table and meshing with said first-mentioned gear, said reversing-gear having projecting pins, substantially as described.

20. The combination with a turn-table, of three sets of gripping devices mounted thereon at substantially equal distances apart, each of said gripping devices being provided with a screw-threaded rod and a nut for positively moving them radially in either direction, and guides secured to the turn-table for holding the gripping devices in their respective positions on the turn-table, each of said rods being provided with gearing, and connections for moving the gripping devices simultaneously to or from the pipe to be gripped and turned, substantially as described.

21. In a well-sinking apparatus, the combination of a turn-table, gripping devices carried thereby adapted to engage the boring-tube, said gripping devices being mounted on swinging supports adapted to swing upward with reference to the boring-tube, whereby they may be moved out of operative engagement with the boring-tube when the boring-tube is lifted, and means for swinging said supports, substantially as described.

22. In a well-sinking apparatus, the combination of a turn-table, gripping devices carried thereby adapted to engage the boring-

tube, said gripping devices being mounted on swinging supports adapted to swing upward with reference to the boring-tube, whereby they may be moved out of operative engagement with the boring-tube when the boring-tube is lifted, means for swinging said supports, and means for locking said supports to hold said gripping devices out of operative position, substantially as described.

23. In a well-sinking apparatus, the combination of a turn-table, a gripping device carried thereby adapted to engage the boring-tube, said gripping device being mounted in a swinging support, whereby it may be moved out of operative engagement with the boring-tube, a stop on which said support rests, and means for adjusting said stop to raise the swinging support, substantially as described.

24. In a well-sinking apparatus, the combination of a turn-table, a gripping device carried thereby adapted to engage the boring-tube, said gripping device being mounted in a swinging support, whereby it may be moved out of operative engagement with the boring-tube, an adjustable cam on which said support rests, and means for adjusting said cam to raise the swinging support, substantially as described.

25. In a well-sinking apparatus, the combination of a base, a turn-table, an inverted peripheral rack carried thereby having an external peripheral groove below said rack, a driving-gear engaging said rack for rotating said turn-table and a plurality of clamps fixedly secured to the base and having rigid teeth which project into said groove to prevent displacement of said turn-table.

26. In a well-sinking apparatus, the combination of a turn-table, supporting devices mounted thereon and movable toward and from the center thereof, gripping devices carried by said supporting devices, and means connected with said supporting devices for

positively moving said gripping devices simultaneously toward or from the center of 45 the turn-table.

27. In a well-sinking apparatus, the combination of a turn-table, three supporting devices mounted thereon and having gripping devices adapted to grip the boring-tube, 50 said supporting devices being substantially equally distant apart and being adapted to travel on said turn-table toward and from the boring-tube, and means adapted to be operated independently of the rotation of the 55 turn-table and connected with said supports for positively moving said gripping devices simultaneously toward or from the boring-tube.

28. The combination with a turn-table, of 60 three sets of gripping devices mounted thereon at substantially equal distances apart, each of said gripping devices being provided with a screw-threaded rod and a nut for moving them radially, connecting-rods 65 and gears connecting said screw-threaded rods and guides secured to the turn-table for holding the gripping devices in their respective positions on the turn-table, substantially as described. 70

29. In a well-sinking apparatus, the combination of a turn-table, and gripping devices carried thereby adapted to engage the boring-tube, said gripping devices being mounted on swinging supports adapted to swing upward 75 above a horizontal plane, whereby they may be swung upward out of operative engagement with the boring-tube to enable the pipe, with its couplings, to pass said gripping devices, said swinging supports being movable 80 bodily, toward, and from the boring-tube, substantially as described.

MATTHEW T. CHAPMAN.
